REGENERATIVE HEAT EXCHANGER FOR
GASEOUS MEDIA

Willy Linder, Essen, Germany, assignor, by mesne assignments, to Koppers Company, Pittsburgh, Pa., a corporation of Delaware

Application May 5, 1938, Serial No. 206,124
In Germany May 5, 1937

2 Claims. (Cl. 48—74)

The present invention relates to regenerative heat exchangers, similar to the well-known stoves of the system Cowper, for preheating or cooling-down gaseous media, said heat exchangers being 5 equipped with refractory checkerwork which is periodically supplied with heat.

The main object of my present invention is to improve the design of these tower-like heat exchangers in such a manner that gases may be 10 withdrawn from or introduced into the heat exchangers at various temperatures.

The solution of this problem, according to the present invention, consists in fitting the heat exchanger with one or several gas outlets and inlets which are arranged at a suitable intermediate level of the checkerwork and in providing the checkerwork with horizontal cross channels at the level of the intermediate gas outlets and inlets in such a way that all the vertical gas conducting channels or other spaces of the checkerwork are connected with the intermediate gas outlet and inlet, or with the individual intermediate gas outlets and inlets when more than one is employed. Further the invention comprises 20 the provision of an annular channel in the brick lining of the heater-jacket, in the zones of the gas outlets and inlets, said channel on the one hand being in connection with the vertical channels of the checkerwork through the horizontal 25 cross-channels and on the other hand with the gas discharge pipe-line.

With the above and other objects of my invention in view, I will now describe a preferred embodiment of my invention on the lines of the 30 accompanying drawings, in which—

Figure 1 is a vertical section through a tower-like heat exchanger for preheating the gases according to my present invention.

Figure 2 shows on an enlarged scale a horizontal section through the heat-exchanger on line II—II of Figure 3.

Figure 3 finally shows on an enlarged scale a vertical section through a part of the heat-exchanger on line III—III of Figure 2.

The gas heater as illustrated on the drawings, is preferably used for the conversion of methane and similar hydrocarbons, or gas containing those constituents, into hydrogen and carbon monoxide (i. e. permanent gases), said conversion being 45 carried out at an increased temperature in the presence of steam or other media. The conversion of methane or the like into permanent gases is a highly endothermic reaction. It is well-known to lead the methane gas to be converted, 50 or the like, mixed with steam in the appropriate

proportion, through a regenerative heat exchanger designed similarly to a blast-furnace hot blast stove, the checkerwork of which, serving for the exchange of heat, has been previously heated up to the desired high temperature. The relatively 5 cold mixture consisting of steam and gas takes up the heat from the hot checkerwork of the regenerator and is thus first heated-up to the temperature necessary for the conversion.

As soon as this temperature has been arrived 10 at, further heat is withdrawn by the gas from a further zone of the checkerwork in order to effect and maintain the endothermic reaction.

In consequence of this, considerably more heat 15 is taken from the checkerwork in the zone of higher temperature endothermic reaction than in the zones situated near the inlet of the cold media. When the checkerwork is heated-up again, the temperature of the waste gases, upon leaving the known heat-exchangers, increases 20 rapidly, after reversal of the regenerative heaters, and the greater part of the heating-up gases leaves the heater at too high a temperature, as the zones of lower temperatures of the checkerwork absorb only a comparatively small quantity 25 of the heat.

Since the temperature of the waste gases varies considerably and since, on the other hand, the temperature of the waste gases leaving the regenerator is relatively low the utilization for 30 other purposes of the sensible heat of the final spent waste heat gases of a heater, in which the conversion of gases containing methane, or other endothermic reactions are carried out, is rendered rather difficult, if not at all practically 35 impossible.

Now the above mentioned difficulty is overcome, according to my present invention, by equipping the heater with means which enable the withdrawal of a part of the hot gases, used 40 for heating-up the checkerwork, in an adjustable quantity from a zone of a higher temperature of the heater, before this part of the hot waste gases goes through the checkerwork zones near the inlet for the relatively cold reaction media, thus 45 by-passing the latter zones.

The heater, as illustrated on the drawings, consists of a casing 1, preferably made of steel plate or another suitable material. The casing 1 is lined inside with a layer 2 of heat insulating material and an inner layer 3 of refractory material. A reaction chamber 7 is formed by the refractory brickwork 3. The chamber 7 is covered on the top by an arch 4. In the arch 4, there is an opening or port 5 which serves in al- 55
